UNITED STATES PATENT OFFICE.

JOHN R. BUECHLER, OF KEOKUK, IOWA, ASSIGNOR TO ALBERT G. WETMORE, OF PLYMOUTH, INDIANA.

CRATE.

1,307,434.

Specification of Letters Patent. Patented June 24, 1919.

Application filed January 8, 1917. Serial No. 141,175.

To all whom it may concern:

Be it known that I, JOHN R. BUECHLER, a citizen of the United States, residing at Keokuk, in the county of Lee and State of Iowa, have invented new and useful Improvements in Crates, of which the following is a specification.

This invention relates to crates of the knock-down type, constructed with a view to permitting ready assemblage of the parts for use or their separation for knock-down shipment.

The improved crate is made up of opposed heads and intervening slats, the latter co-operating with the heads in the particular manner for detachable connection with the heads while yet insuring a particularly substantial structure when the parts are in crate forming relation, the slat members are wholly free of connection one with another to permit close storage when in knock-down relation; the construction also permitting the use of a variable number of slats with the particular heads, in accordance of the nature and character of contents with which the crate is to be used.

The invention also contemplates an auxiliary fastening means, whereby the slats may be held against separation from the heads in any direction, to thereby permit the use of the crate when but partly filled or under other circumstances.

The improved crate in its preferred details is shown in the accompanying drawings in which:

Figure 1 is a perspective view with a crate constructed according to this invention.

Fig. 2 is a perspective view of a hook clip for connecting the slats to the heads.

Fig. 3 is a vertical sectional view through a slat and both heads in crate forming relation.

Fig. 4 is a horizontal section on line 4—4 of Fig. 3.

The improved crate is made up of opposed and preferably duplicate heads, each including an annular band or ring member 1, and brace strips 2 extending across said member and preferably, though not necessarily, secured to one edge thereof. If desired a further brace strip 3 may be arranged within the band, the ends of the strip 3 bearing against the band at diametrically opposite points, and said strip 3 preferably being arranged across the strips 2.

The upright or what may be termed the side wall of the crate includes a series of slats 4 of identical construction. Each slat, preferably though not necessarily of wood, is of a length and thickness determined by the size and strength desired for the particular crate, and is provided at each end with a terminal hook clip, which clips are designed to removably engage the annular head members 1.

As here shown the clip members each comprises a U-shaped metallic section, having a width corresponding to the similar dimensions of the slat, with one side wall 7 of such members removably secured in fixed relation to the slat by bolts 13 passed through the slat from the inner side and through holes 9 in the wall 7. The hook clips are arranged so that the end walls 6 thereof rest upon and bear squarely against the ends of the slats, the bolts 13 having their heads counter-sunk in what may be termed the inner surfaces of the slats, and having terminal nuts 14 to secure the hook clips to the slats. The hook clips are of such dimension that the remaining or relatively inner walls 8 are, when the clips are secured to the slats, spaced from the relatively inner sides of the slats a distance approximately equal to the thickness of the ring members 1 of the heads, and the length of the side walls 7 and 8 is preferably slightly greater than the vertical dimension of the wall of the ring member 1.

As thus constructed, each slat is provided at each end with a removably secured hook clip, which clips open toward each other in position to receive the ring members of the respective heads.

In making up the crate the lower head is secured within the clips of the desired number of slats, so that said slats form in effect a skeleton side wall, rising above the lower head member. The material to be crated is then placed within this side wall, and the upper head member moved downwardly within the upper ends of the slats until the hook clips of the latter may be moved into position to engage the ring member 1 of the upper head.

The invention contemplates a means for securing the ring member of the upper head in the hook clips. As here shown this means comprises nails or similar fastening strips, which are adapted to be passed through openings 10 and 12 formed in the margins of

the clips below the adjacent edge of the head, these nails or fastenings passing through the clip and slat, and being of a length to permit their terminals to be bent laterally on the outside of the clips to prevent accidental disconnection.

In the particular form here shown it is noted that the band of each head is rectangular in section, and the clip 5 correspondingly shaped. This prevents possibility of tilting movement of the heads and insures a comparatively rigid structure when the parts are assembled.

The salient feature of the invention resides in the heads made up as an entirety and a series of independent slats, having hook clip terminals to engage, but remain wholly free of direct connection with the heads. The importance of this arrangement is apparent when it is understood that by such, any desired number of slats may be used with a particular crate to thereby render such crate as strong as necessary for the particular purpose. Furthermore the slats are without connection one with another and may be conveniently bundled in comparatively small space for reshipment, when in knock-down relation.

Having thus described the invention, what is claimed as new is:

1. A crate comprising end members or

heads spaced apart, each embodying a ring-shaped marginal member, slats extending between said heads and arranged in lapping engagement with the latter, rectangular U-shaped coupling members secured to the ends of each slat and engaging over the marginal member of each head and provided in the side portions with aligned openings, and a fastening member arranged to be positioned in said openings and inwardly of said marginal member for detachably coupling the crate members together.

2. A crate comprising end members or heads spaced apart, each embodying a ring-shaped marginal member, slats extending between said heads and arranged in lapping engagement with the latter, rectangular U-shaped coupling members at the ends of said slats, each coupling member comprising one end and two parallel side portions, one of the latter secured to the outer face of the slat by suitable means, the other side portion arranged to lap the inner face of the marginal member, said side portions provided with aligned openings, and a fastening member arranged to be positioned in said openings and inwardly of said marginal member for coupling the crate members together.

In testimony whereof I have hereunto set my hand.

JOHN R. BUECHLER.
